UNITED STATES PATENT OFFICE.

CHARLES H. BIRCH, OF JOLIET, ILLINOIS.

APPARATUS FOR COMMINUTING MATERIALS.

Application filed October 31, 1924. Serial No. 747,083.

My invention belongs to that general class of apparatus designed to pulverize, powder or comminute materials, and more particularly relates to an apparatus adapted for comminuting coal and like materials and feeding the same, for example, into a firebox. The device has among its objects the production of an apparatus of the kind described that is simple, convenient, compact, durable, reliable, efficient and satisfactory for use wherever found applicable. More particularly it has as an object the production of a device which will be particularly suited for the comminuting of fuels and discharging the same continuously in a desired manner to where required. The invention has also as an important object the production of a machine that will be as quiet and noiseless and free from vibration as possible, which will be economical in operation and which may be regulated for varying conditions.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a sectional view through my improved apparatus taken substantially on line 1—1 of Fig. 2, with some parts omitted to more clearly show the construction;

Fig. 2 is a sectional view taken substantially on line 2—2 of Fig. 1, with some parts omitted to avoid confusion;

Fig. 3 is a sectional view taken substantially on line 3—3 of Fig. 2;

Fig. 4 is a sectional view of one of the shaft bearings;

Fig. 5 is a sectional view taken substantially on line 5—5 of Fig. 2;

Fig. 6 is a sectional view taken substantially on line 6—6 of Fig. 5; and

Fig. 7 is a sectional view taken on line 7—7 of Fig. 5, with drum turned to another position.

Referring to the drawings, in which the preferred embodiment of my invention is shown, I provide a casing which may be made in one or more parts of the desired

size, shape and material. The particular casing illustrated for convenience in construction and in assembly is made up of parts 1, 2, 3 and 4, with associated parts 6, 7 and 8, all of which may be secured together in any satisfactory manner.

Arranged within the casing part 1 are rolls 9, 10 and 11. The material is fed into the hopper 6 from any suitable source and there is picked up by the feeder. The feeder is most clearly shown in Figs. 2, 5 and 6, and consists of a drum 15 provided with the cooperating part 16. This drum 15 may be made solid or, if desired, tubular, as shown, so as to reduce weight. The drum 15 is provided with suitable supporting shaft 19 and arranged in the bearings on the casing. The member 16 carried thereby is adjustable relative the roll so that the amount of material fed may be varied as desired. As shown, the same is provided with a shaft 20 supported on the roll and controlled from the exterior of the casing, as herein described. The roll (see Figs. 2, 5 and 6) is recessed as at 21 and the member 16 so arranged that it may be moved into the recess and fill the same, or be moved into the position shown in Fig. 2, or similar position. Arranged on the end of the shaft is a member 23 provided with the dogs 24 and 25. These dogs are arranged to cooperate with the cams 26 and 27 respectively to control the movements of the member 16 in and out of its recess 21. As shown, 28 is an adjustable sleeve projecting to the exterior of the casing and provided with an operating lever 29, by means of which the cam 26 may be adjusted. The cam 27 is mounted on or formed as part of the casing.

Generally I prefer to form the casing part so that the cam mechanism is enclosed in a chamber so that particles of material cannot get to the parts, and likewise so protect the bearings at the opposite ends. As shown, the casing walls 30 at either end provide the enclosed construction. The member 15 is power-driven, as will be more fully explained hereinafter.

The roll 9 is arranged on a shaft 32, suitably supported on the casing. The roll 10 is made up of a number of sections consisting of the end sections 33 and intermediate sections 34. The several sections are secured together by a rod 35 or equivalent means, 36 being a spacer extending between the end sections 33 and also protecting and reinforc-

ing the rod or shaft 35. Roll 11 is arranged on the shaft 37, projecting to the exterior of the casing and driven as will be hereinafter described. As will be noted, 5 rolls 9 and 11 are positively driven, while the sectional roll 10 is carried by rolls 9 and 11 and driven thereby. I prefer to provide the roll 11 with one or more, preferably a series, of recesses 38, the purpose of which 10 is hereinafter described.

Arranged at one side and below the rolls 15 is a beater mechanism consisting of a driven shaft 39 provided with a sleeve 40, to which are secured beaters 41, the same being pivotally secured to wings 42 by means of pins 15 or bolts 43 or the equivalent. These beating members 41 I prefer to provide with faces 45, and I provide a serrated face 46 on the part 7, as well as a serrated face member 48. Member 48 is preferably made removable so that it may be replaced or removed for any reason. The shaft 39 may 20 be driven in any suitable manner not necessary to describe herein. Generally I prefer to 25 mount the shafts 39, 37 and 32 in bearings substantially as indicated in Figs. 1 and 4.

Referring particularly to Fig. 4 in which 30 one roll bearing is shown, 51 is a sleeve mounted in the casing 1, which carries the bearing member 52. The sleeve may be secured in place in any suitable manner as by bolting or otherwise. I have shown the member 52 provided with a bushing 53 of suitable bearing material, 54 being washers 35 between which is arranged a felt washer 54', or the equivalent. The parts 51 and 52 are so provided with openings 51' so that any dust or grit accumulated from the interior of the casing may drop out of the bearing 40 box. With this construction the part 51 may be removed and with it the bearing 52, the parts being so designed that the opening is sufficient to permit withdrawal 45 of the roll therefrom without disassembling the casing. This construction has the 50 advantage of being proof against the admission of dust and grit against the bearing and likewise permits easy assembling and disassembling of the machine or the replacement of parts. This shaft, through suitable sprockets and sprocket chains or equivalent means, is arranged to drive the beaters, together with the rolls 9 and 11 and the feed roll 15, the driving connections being 55 indicated in dotted lines in Fig. 2, together with the direction of rotation of the several members. I prefer to provide a baffle 55, as shown in Fig. 2.

Arranged within the casing is a fan or 60 blower 56 of suitable size, shape and design, the same being shown mounted on a driving shaft 57. This shaft may be driven in any suitable manner, the construction shown consisting of beveled gearing 58 and 59, shaft 60 and pulley 61, which is belted to

pulley 62. It may be mentioned that I prefer to use a cross-belt 63, as most clearly shown in Figs. 1 and 2, so that the operation of the blower and other parts of the mechanism work in unison. Suitable bearings, preferably anti-friction bearings, are provided for the shafts 57 and 60, it being understood that any equivalent construction other than that shown may be employed. The shaft 57 also carries a member 64, which 70 is chambered as indicated at 65 and provided with the rims 66 and 67. The rim 67 is of a size to allow a space 68 between the casing and the edge of the rim, while the upper portion 66 is so proportioned as to 75 leave the space 69 between the rim and casing. The member 64 is provided with openings 70 and is open at the bottom, as indicated at 71. Arranged at the open bottom 80 is a valve member 72 which is movable up or down to partially close or uncover the opening 70. This member is shown pivotally supported by arms 74 from the shaft 75, which is controlled by an arm 76. This arm may be maintained in the position 85 desired by a pin 77, or the equivalent, adapted to engage one or more holes in the casing so as to maintain the same in the desired adjustment. 78 represents the 90 baffle plate interposed between the member 64 and the casing outlet which is at 79.

The operation of the device may be briefly described as follows: Assuming that the member 16 is in the position shown in Fig. 2, the cam 26 turning the same to this 100 position, any coal which is discharged into the hopper 6 through the opening 14 will be picked up by the feeding roll, consisting of 15 and 16, and carried over the top of the same, the amount so picked up depending 105 upon the position of the same and resulting adjustment of 16 and the air current. As soon as it passes over the top, it tends to discharge the material which flows off and down the sloping bottom 5 into the beater. As the roll 15 tends to rotate, dog 25 will 110 engage cam face 27 and rock member 16 in the position to fill the recess 21 and clear the bottom wall of 6, as shown in Fig. 7, thereby throwing out any material therein. As the roll continues to rotate, however, it 115 is thrown back to the position shown in Fig. 2 and again picks up and carries the load. Obviously, the location or adjustment of the cam 26 will vary the amount of material 120 that will be picked up, as the member 16 will be varied in its adjustment.

The material, while traveling down from the feeder, will be thoroughly mixed with the air that enters through the opening 22. Consequently, any dust or finely comminuted material will follow the air current directly 125 into the separator where the final separation takes place. The heavy material coming down from the feeder passes into the beater 130

compartment where it is partly reduced, especially the large pieces, by the hitting action of the beaters which also throws the material against the serrated stationary surface. The beaters will then throw any particles that are too heavy to be picked up by the passing air current into rollers 10 and 11 which reduce the material to such a fineness that it can be picked up by the said current. To accomplish this, it may have to pass through the rolls several times. Any large pieces not readily broken up by the beaters are also thrown into said rolls, but being too large to be fed in between the rolls in the ordinary way, are forced through by the recesses 38 in roll 11. These recesses act as pushers. All finely comminuted material is carried up by an air current having a desired intensity or suction produced by the fan. As it is impossible to get a uniform separation of the coarse from the fine material in a space where so much commotion exists as in the space directly above the beaters and rolls, the material is passed through a separator. The function of this is to receive the high velocity air current with all the material in it and to gradually reduce said velocity to a point that is too slow to carry the heavier particles in suspension. The result is the coarse particles drop out of the air current and fall onto the rim 67, thence through space 68 and is finally thrown into rolls 10 and 11 and reduced. The fine particles in the separators are carried with the air current upwards and pass through space 69 where the velocity again is high.

As shown in Figs. 1 and 2, the space provided for separation has such a shape that will first produce a gradual reduction in velocity to cause separation, and then as the current passes closer to the contracted space 69, the velocity is increased to allow the same volume of air to pass through as entered through valve 72. From the separator the current passes through the fan and then to a collector or other suitable receiving apparatus.

The apparatus herein shown has many advantages. The feeder, with its adjustable cam mechanism, by means of which the amount of feed can be varied between zero and the maximum, while the machine is running does not employ ratchets, gears or the like, and is desirable and efficient. With the three roll arrangements for crushing, the big roller made up of the segments being combined axially, there is no wearing at the end discs against the side plates. This is accomplished by means of the guide rod which also, in the event that a piece of material gets under one of the discs, limits the disc movement, and that disc may rise until the wall of the hole at the center of the segment strikes the tie rod, after which the

crushing effect is increased, due to the weight of the additional rollers. This permits a piece to get under the segment and start to feed before the entire weight of the roll segments are exerted upon it. If the segment is sufficient to crush it, it is crushed, but if necessary, owing to its size, the weight of the several segments will be effective to crush the lumpy material.

The rotating beaters not only reduce and beat up the material, but at the same time the same serves as a feeder for the crushing rolls as material that is too large to be drawn up by the fan will be thrown into the crushing rolls until it is finally comminuted to the point where it is carried along from the casing. The fineness of the material is controlled by regulating valve 72. Moving this valve upward will decrease the amount of air entering the separator, and since the ratio of the sectional area of the separating chamber to the inlet area can be varied, it follows that reducing the volume entering the separator will result in a similar reduction in velocity of the moving air in the separating chamber. The slower the velocity of the air in said separating chamber, the finer will be the material delivered by the fan. It is understood that the separator and fan can be driven independently of each other in any desired manner, also that the fan can be placed horizontally if suitable.

The construction is such that substantially a uniform product is discharged from the device and the material all thoroughly comminuted. If the member 16 is arranged so that no material is carried over by the roll 15, the roll will merely revolve or rotate, and consequently it is possible to control the discharge of the material to correspond with the output required.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the character described and in combination, a casing provided with an inlet and outlet, a blower having rotatable vanes arranged to discharge comminuted material through said outlet, means for regulating the passage of material through the casing, said last mentioned means comprising an apertured member constrained to rotate with the vanes, and valve means for controlling the passage of material through the aperture in said member.

2. In a device of the kind described and in combination, a casing provided with an

- inlet and outlet, feeding means at said inlet, and in combination, a casing, crushing mechanism comprising a plurality of spaced driven rolls rotatably journaled in the casing and an idler roll arranged therebetween and carried thereby, said idler roll consisting of a plurality of sections operatively secured together and having independent relative movement, one of said spaced rolls having a plurality of recesses therein. 70
- 5 5. In a device of the kind described and in combination, a casing provided with an inlet and outlet and divided intermediate the inlet and outlet to provide associated minute material through said discharge port, and adjustable means for regulating the passage of material through the casing, said adjustable means including a rotatable apertured plate forming a partition across the casing. 75
- 10 3. In a device of the character described and in combination, a casing provided with an inlet and outlet and divided intermediate the inlet and outlet to provide associated compartments, a fan in one compartment for causing a flow of comminuted material thereto from the other compartment and discharging the material through said outlet, means for controlling the passage of material into the fan compartment, said last mentioned means comprising an apertured member rotatable with the fan, and means for controlling the flow of material through the aperture in said member. 80
- 15 20 4. In a device of the kind described and in combination, a casing provided with an inlet and outlet, means for controlling the passage of material into the casing, means for comminuting the material consisting of beating means and cooperating crushing means, a shaft projecting into the said casing and provided with a rotary part substantially constituting a partition across the casing and having ports for the passage of material adjacent the center thereof, a blower carried by said shaft constructed to induce a flow of material from said comminuting means through the casing and out through said outlet. 85
- 25 30 35 45 50 55 60 65 70 75 80 85 90 95 100 105 110 115 120 125
- 30 5. In a device of the kind described and in combination, a casing provided with an inlet and outlet, adjustable means for controlling the passage of material into the casing, means for comminuting the material consisting of beating means and cooperating crushing means, a shaft projecting into the said casing and provided with a rotary part substantially constituting a partition across the casing and having ports for the passage of material therethrough adjacent the center thereof, a blower carried by said shaft above said rotary part constructed to induce a flow of material from said comminuting means through the casing and out through said outlet. 110
6. In an apparatus of the kind described and in combination, a casing, crushing mechanism comprising a plurality of spaced driven rolls rotatably journaled in the casing and an idler roll arranged therebetween and carried thereby, said idler roll consisting of a plurality of sections operatively secured together and having independent relative movement. 115
- 65 7. In an apparatus of the kind described and in combination, a casing provided with an inlet and outlet and divided intermediate the inlet and outlet to provide associated compartments, a fan in one compartment for causing a flow of comminuted material thereto from the other compartment and discharging the material through said outlet, means for controlling the passage of material into the fan compartment, said last mentioned means comprising an apertured member rotatable with the fan, and means for controlling the flow of material through the aperture in said member. 120
8. In an apparatus of the kind described and in combination, a casing, crushing mechanism comprising a plurality of spaced driven rolls rotatably journaled in the casing and an idler roll arranged therebetween and carried thereby, said idler roll consisting of a plurality of sections operatively secured together and having independent relative movement, and beating mechanism associated therewith. 125
9. In a machine of the class described and in combination, a casing, means for receiving and discharging comminuted material from the casing, said means including a shaft, a fan arranged thereon, a rotary separator arranged in the path of the comminuted material as it travels toward said fan, said separator arranged to return the heavy particles to the source of supply, and valve means associated with the rotary separator for controlling the passage of comminuted material therethrough. 130
10. In a device of the kind described and in combination, a casing provided with an inlet and outlet, means for feeding material into the casing, means for comminuting the material consisting of beating means and cooperating crushing means, a shaft projecting into the said casing and provided with a rotary part substantially constituting a partition across the casing and having ports for the passage of material adjacent the center thereof, a blower carried by said shaft constructed to induce a flow of material from said comminuting means through the casing and out through said outlet. 135
11. In a machine of the class described and in combination, a casing, comminuting mechanism arranged therein and means for receiving and discharging the comminuted material from the casing, including a shaft, a fan arranged thereon, a disc arranged on said shaft in the path of the comminuted material passing from said comminuting mechanism to said blower, said disc having a valved port, and means for regulating the fineness of material passing to the fan through said valved port. 140
12. In an apparatus of the kind described, a casing and associated casing parts having an inclined bottom wall with the material inlet adjacent the raised portion of the bottom wall, a feeding mechanism arranged adjacent said inlet, beating mechanism arranged at the lower end of said bottom wall, crushing mechanism arranged intermediate 145

said beating mechanism and feeding mechanism, said casing having an outlet, a power driven blower arranged between said outlet and said beating and crushing mechanism, 5 a separator arranged between said blower and beating and crushing mechanism, and means for controlling the passage of material to said blower and its discharge from the outlet of the casing.

10 13. In an apparatus of the kind described, a casing and associated casing parts having an inclined bottom wall with the material inlet adjacent the raised portion of the bottom wall, an adjustable feeding mechanism 15 arranged adjacent said inlet, beating mechanism arranged at the lower end of said bottom wall, crushing mechanism arranged intermediate said beating mechanism and feeding mechanism, said casing having an 20 outlet, a power driven blower arranged between said outlet and said beating and crushing mechanism, and means for controlling the passage of material from said beating and crushing mechanism to said 25 blower and discharge outlet of the casing.

14. In a device of the kind described and in combination, a casing having a plurality of compartments and having an inlet and an outlet, crushing means arranged in one 30 of said compartments, rotary means arranged in the other compartment for blowing crushed material through the outlet, and an apertured member constrained to rotate with said rotary means and forming a partition between said compartments.

35 15. In a device of the kind described and in combination, a casing having a plurality of compartments and having an inlet and

an outlet, crushing means arranged in one of said compartments, rotary means arranged in the other compartment for blowing crushed material through the outlet, an apertured member constrained to rotate with said rotary means and forming a partition between said compartments, and means as 40 associated with said apertured member for controlling the flow of crushed material therethrough.

16. In a device of the kind described and in combination, a casing having a plurality 50 of compartments and having an inlet and an outlet, crushing means arranged in one of said compartments, rotary means arranged in the other compartment for blowing crushed material through the outlet, an 55 apertured member constrained to rotate with said rotary means and forming a partition between said compartments, and valve means associated with said apertured member for controlling the flow of crushed material therethrough.

17. In a device of the kind described and in combination, a casing, a pair of spaced rolls rotatably journaled in the casing, means for driving said rolls, a third roll carried by said pair of rolls and comprising a plurality of relatively movable members, 65 beating mechanism disposed in the casing, a fan disposed in the casing, an apertured member constrained to rotate with the fan, 70 and valve means associated with said apertured member.

In testimony whereof, I have hereunto signed my name.

CHARLES H. BIRCH.
